Int. Cl. D26—02

U.S. Cl. D48—20

FIG. 1 is a perspective view of a high intensity lamp illustrating my new design, with the telescopic mounting assembly for the shade fully extended;

FIG. 1 is a rear elevational view of the same;

FIG. 3 is a top plan view of the same;

FIG. 4 is a perspective view of said lamp with the telescopic mounting assembly collapsed, and shade in the stowed position relative to the base;

FIG. 5 is a front elevational view of the lamp in the position as illustrated in FIG. 1;

FIG. 6 is a side elevational view of the same.

I claim:

The ornamental design for a high intensity lamp, substantially as shown and described.
